US00D970385S

(12) **United States Design Patent** (10) **Patent No.:** **US D970,385 S**
(45) **Date of Patent:** **** Nov. 22, 2022**

(54) **NECKLACE**

(71) Applicant: **Harry Winston SA**, Plan-les-Ouates (CH)

(72) Inventor: **Delphine Abdourahim**, New York, NY (US)

(73) Assignee: **Harry Winston SA**, Plan-les-Ouates (CH)

(**) Term: **15 Years**

(21) Appl. No.: **29/751,157**

(22) Filed: **Sep. 18, 2020**

(30) **Foreign Application Priority Data**

Mar. 27, 2020 (WO) WIPO93600

(51) **LOC (13) Cl.** **11-01**

(52) **U.S. Cl.**

USPC **D11/7; D11/3**

(58) **Field of Classification Search**

USPC D11/6-8, 10, 11, 16
CPC A44C 13/00; A44C 15/00; A44C 15/005;

A44C 25/001
